(57) **CLAIM**

The ornamental design for a display screen or portion thereof with graphical user interface, as shown and described.

DESCRIPTION

FIG. 1 is a front view of a first image of a first embodiment of a display screen or portion thereof with graphical user interface showing my design;

FIG. 2 is a front view of a second image thereof;

FIG. 3 is a front view of a first image of a second embodiment of a display screen or portion thereof with graphical user interface showing my new design; and,

FIG. 4 is a front view of a second image thereof.

The first and second embodiments comprise a display screen having an animated graphical user interface. In the first embodiment, the appearance of the transitional image sequentially transitions between the images shown in FIGS. 1 and 2. In the second embodiment, the appearance of the transitional image sequentially transitions between the images shown in FIGS. 3 and 4. The process or period in which one image transitions to another image forms no part of the claimed design.

The broken line showing of an outer edge of a display screen in FIGS. 1-4 represents environmental subject matter and form no part of the claimed design.
